SLOW-MOTION ELECTRICAL PICTURE
REPRODUCTIONGeorge C. Sziklai, Princeton, N. J., assignor to
Radio Corporation of America, a corporation of
Delaware

Application November 1, 1943, Serial No. 508,566

10 Claims. (Cl. 178—6.8)

1

The present invention relates to the reproduction of images electrically and more particularly to increasing the total time of reproduction of images by electrical methods so that fast phenomena may be studied.

Heretofore, in the reproduction of images by electrical means, it has been necessary to electrically reproduce an image simultaneously with the scanning of the image at an image signal generating point. By the term "image" in the foregoing and in the complete description of the invention which is to follow is meant an image of any picture, object or view, or an image representing a curve illustrating phenomenon under observation.

In accordance with the present invention, the time interval of reproduction of an image may vary with respect to the time interval during which an original phenomenon occurred. These time intervals, in accordance with the invention in the preferred form, are equal or substantially equal, and the time intervening between the reproduction of a series of images varies and may be considerably prolonged. This is permissible since the illusion of motion in any event is possible only because of persistence of vision. This physiological phenomenon may be aided by employing a reproducing medium having an image persistence characteristic.

The primary object of the invention is to decrease the speed of reproduction of electrically reproduced images.

Another object of the invention is to stretch the time interval normally existing between images of a series of electrically produced images.

A further object of the present invention is to provide for the storage of image signals in a television system.

A still further object of the invention is to provide control means for an image signal storing arrangement.

Other objects of the invention will become apparent when the following specification and claims are read in connection with the accompanying drawings, wherein:

Fig. 1 is a diagrammatic illustration of an image signal storing system embodying the present invention;

Figs. 2 and 3 are curves referred to in the description of the operation of the apparatus of Fig. 1;

Fig. 4 is a schematic showing of a system embodying the invention in its preferred electronic controlled form;

2

Fig. 5 shows a characteristic curve of a portion of the apparatus of Fig. 4; and
Fig. 6 shows another modification along the lines of Fig. 4.

Referring to Fig. 1 of the drawings, an arrangement is shown in schematic form which illustrates the basic principle of the present invention. Reference character 10 indicates a device for generating an image signal and is illustrated as 10 a cathode ray camera or transmitter scanning tube of well-known design, such as an "ionoscope" or an "Orthicon." For example, the generation of television signals may be carried out in the manner disclosed in a patent to Bedford, 15 2,192,121, granted February 27, 1940. A suitable synchronizing arrangement is shown in a patent to Seeley, 2,256,530, granted September 23, 1941. Smith Patents 2,132,654 and 2,132,655, both granted October 11, 1938, show scanning control 20 generators which may be employed with the camera, transmitter or scanning tube. These patents are mentioned solely because of the fact that they illustrate one suitable form of a cathode-ray scanning system. Any form of mechanical or electronic scanning device may be employed 25 when practicing the invention. The tube 10 comprises a highly evacuated envelope 12, having therein an electron gun 14 for producing an electron beam and the usual deflecting arrangement 30 16 for producing horizontal and vertical deflection of the ray. The usual saw tooth wave generators (not shown) as well as control signal pulse generators (also not shown) are included to furnish the deflecting currents or voltages to be applied to the deflecting unit 16. In the latter instance the deflecting unit 16 will be composed of electrostatic deflecting plates in space quadrature. It will be understood that electrostatic or electromagnetic deflection may be employed.

A mosaic 18 of photoelectric elements is also contained in the envelope 12. An optical image of the subject to be transmitted is projected upon the mosaic 18 by an optical lens system 21 whereby an electrostatic image is formed on the 45 mosaic. Thus, when the mosaic is scanned by the cathode ray, image or video signals are produced which appear across an output resistor 23. The image signals are amplified by an image signal amplifier 24, the output of which is connected to the distributor 27.

The subject which is to be scanned by the tube 10 is shown by way of example as a motion picture film 31 having the usual successive views numbered 1 to 3 and so on. Whereas three frames 55 have been shown illustratively on the film 31,

it will be understood that the series of frames assumed to be of interest and which is to be scanned by the cathode ray tube 10 may comprise any reasonable number. Three frames have been shown to simplify the disclosure and description of the principles involved. The direction of intermittent movement of the film 31 is indicated by the arrow. It will be understood that the film 31 has been selected to simplify the discussion of the operation which is to follow. Usually, the cathode ray tube 10 will be employed, to scan a field of view having moving objects therein, or the screen or target of a cathode ray oscillograph or other laboratory instrument which is exhibiting a pattern representing a rapidly changing characteristic curve which is to be studied.

From the apparatus thus far described, it will be seen that the film 31 is moved intermittently to bring the frames 1 to 3 successively into position before the lens 21. Image signals representing the series of views appearing on the frames 1 to 3 will be amplified by the amplifier 24 and will be furnished to the brush 26 of the distributor 27.

A series of storage repeaters 37, numbered 1 to 3, are shown as being connected to the contact studs 38 of the distributor 27. These storage repeaters may be of any known type. For example, the image multiplier camera tube illustrated on page 326 (Fig. 11.16) of the textbook "Television" by Zworykin and Morton, published by John Wiley and Sons, Inc., in 1940 may be used for this purpose. In using the double mosaic types of storage tubes, as disclosed by the Zworykin and Morton reference, one electronic gun structure is employed to store a charge image on the mosaic of the tube. The other gun structure is employed to scan the opposite side of the mosaic to produce signals representing the stored image. Image or video signals may be applied to the second anode which is associated with the first gun structure, or to a beam modulating electrode of the electron gun with the result that the individual elements of the mosaic will assume a potential relative to a datum level which is dependent upon the electron beam velocity as measured by the second anode voltage relative to the cathode or by the modulation of the beam when the image signal modulation is applied to the control electrode of the gun. When the opposite side of the mosaic is scanned by the cathode ray beam of the second gun structure, output signal energy will be derived from the second anode associated with the second gun structure due to release (in known manner) of the stored charges.

The output connection 39 of each storage repeater is connected to a contact stud 41 of a rotary distributor 44. The brush arm 46 of this distributor is connected by way of a conductor 49 to the usual image signal channel of a television signal transmitting system which is adapted to be connected to a television signal reproducer 51.

The storage repeaters 37, as stated above, may be of the type which release a storage signal upon the application of a bias voltage of a selected polarity and magnitude which controls a beam that scans over the storage mosaic. This biasing voltage may be applied from a conductor 52 in communication with a suitable source of biasing potential to the brush arm 54 of a mechanical distributor 56. The biasing circuits of each of the storage repeaters 37 are connected to a contact stud 58 of the distributor 56 over a conductor 60.

Referring to Fig. 2 of the drawings, the general

nature of the image signals applied to the brush 26 is shown. Each portion 59 of a signal represents the scanning of one frame and comprises a section 61 representing varying light values and the intervening line retrace section 62 during which the known blanking and synchronizing signals are to be added in known manner (not shown). Only three sections of 61 and 62 are shown illustratively, but it will be understood that many more of these actually will be included. The exact number is more or less immaterial in the description of the present invention.

The vertical retrace time 63 occupies a fraction of the time of the total image portion 59. Solely for purposes of illustration and so that the rotational speeds of the commutators shown illustratively may be an even number of revolutions per minute, the time occupied by the image portion 59 of the signal is assumed to be .03 second, and the vertical retrace time 63 is assumed to be .005 second. Three sections or frames of signal series 59, 64, and 66 are shown which may correspond to the frames 1 to 3 of the film 31.

By the arrangement disclosed in Fig. 1, the time delay between successive signal series for the several film frames may be increased as shown in Fig. 3 of the drawings. The video portion 59 of the signal 52 is indicated by 59a and its beginning is shown as occurring at the end of the time interval occupied by the signal portion 59. The delay time from the beginning of the signal 59 to the beginning of the signal 59a is therefore, under the timing assumed by way of example, .03 second. The time interval 63 of Fig. 2 is represented at 63a on Fig. 3 and is now .19 second. The image signal representing the second frame 64 is indicated by reference character 64a on Fig. 3, and the next successive frame on Fig. 3 is indicated by reference character 66a. From an inspection of Figs. 2 and 3, it will be seen that the scanning of frames 1 to 3, illustrated by the wave form of Fig. 2, occupy one tenth of a second. The time for the slow motion reproduction of the scanning of frames 1 to 3 by the television signal reproducer 51 represented by the wave form of Fig. 3 occupies a time of 470 milliseconds.

To prevent operation of the video amplifier 24 until the third frame signal 66a has been discharged from the third storage repeater 37, a connection 68 (Fig. 1) is provided which is connected to a conducting segment 69. A brush arm 70 sweeps over this segment to apply a cut off bias to the amplifier 24 after the signals 59, 64, and 66 have been registered.

With the distributor brush running at a speed of 600 R. P. M., the shaft 72 (Fig. 1) is running at a speed of 120 R. P. M. so that the storage repeaters 37 are biased to discharge their stored signals in timed relationship with the sweep of the brush 46 over the distributor segments 41.

Electronic switches may replace the mechanical switching means. Electronic switches per se are well known and accordingly are not illustrated in connection with Fig. 1 and are not shown in detail in connection with Fig. 4. Suitable forms of such devices are shown by Roys et al., Patent No. 2,089,430, granted August 10, 1937, and by Shumard, Patent No. 2,146,862, granted February 14, 1939.

Fig. 4 of the drawings shows diagrammatically the preferred embodiment of the invention. In this figure the output of the amplifier 24 of Fig. 1 is applied to a switching circuit 76. This switching circuit may be of the type disclosed in

Patent No. 2,113,011 to White, granted April 5, 1938.

A series of signal storage tubes 78 is provided. For illustrative purposes, three of the tubes 78 are shown by Fig. 4 of the drawings, and these tubes may be employed to store the signals from three successive scanning operations of the transmitting scanner 10. Tubes of this general type are illustrated and described in a British patent to V. K. Zworykin, No. 434,890 of 1935, and a United States patent to Harry Branson, No. 2,257,562, granted September 30, 1941.

Each tube 78 is provided with an electron gun construction 81 and includes a source of cathode rays 82, a control grid 83, and an anode or accelerating electrode 84. In addition, there is provided a cathode ray deflecting arrangement 86 which may be similar to the deflecting arrangement 16 of the scanner tube 10. This deflecting arrangement serves to deflect the cathode ray beam so that it moves within the tube envelope 88 under control of a suitable deflecting field applied to the deflecting coils or deflecting electrodes from an external source (not shown) which is either the same source used to control the picture scanning cathode ray tube 10 or any scanning source. As a matter of fact, the target may be scanned in a fashion different from the line by line method, for example, spiral or other curvilinear fashions are applicable.

Varying potentials are applied under the control of the video signals to the grid electrode 83, herein considered as the control electrode, to control the intensity of the electron beam emitted from the cathode emitter 82 in proportion to the light value of the image being scanned. In order to focus suitably the cathode ray, the usual focusing electrodes including the electrode 84 are provided as shown in Fig. 4 of the Branson patent referred to above. The conical inner portion of the tube envelope 88 is in the form of a control electrode or where desired a separate electrode 91 of conical shape is provided. Adjacent the end portion of the tube there is suitably supported a mosaic electrode 100 which includes an insulating plate 92 upon which is suitably deposited a coating 93 of isolated globules. Immediately behind the insulating plate member 93 there is positioned a conducting signal plate member 96. To all of the electrodes suitable connections to supply operating and control voltages are made.

The grids 83 of each tube are biased to a different negative value by a connection 99 so that in order to remove the bias and render the tube operative, different external positive biasing voltages are provided from the switching circuit 76. Referring to Fig. 5 of the drawings, the bias on each successive tube applied by its connection 99 is illustrated by the curve 102. It is assumed for purposes of illustration that a zero bias applied to the grid 83 of each tube will operate, that is to say, the cathode ray beam in that tube will become active and may be modulated by voltage variations applied to its grid. The curve 103 representing the output of the countercircuit which is added algebraically to the bias on each grid increases in the positive direction by successive steps as shown so that each tube 78 in the series becomes successively operative. In this manner successive image signals from successive frames scanned by the tube 10 will be stored electrostatically on the mosaic 100 and this storage signal will be preserved until it is released by a successive scanning of the electron beam, the inten-

sity value of which is maintained substantially constant.

The storage signal from each tube is collected by the collector anode 91 during the scanning by the beam when it is maintained at constant intensity and is fed to the grid of an amplifier tube. One amplifier tube is shown for each of the storage tubes 78. The first storage tube output from its collector 91 is fed over a connection 106 to the grid 108 of an amplifier tube 109. The outputs of the remaining storage tubes of the series are connected respectively to grids 110 and 111 of amplifier tubes 112 and 114.

The amplifying tubes 109, 112, and 114 are biased to cut off by signals from the switching circuit 76 applied over connections 115, 116, and 117 during all times except when the corresponding storage tubes are discharged and the electrical impulses corresponding to the delayed picture frame are to be transmitted to the line amplifier.

With the arrangement shown in Fig. 4 controlled in a preferred manner from an electronic switching circuit 16 rather than by mechanical distributors as in Fig. 1 of the drawings, a more flexible timing of the successive steps in the operation may be realized. For example, with the scanning tube 10 operating at normal television scanning frequency interlaced or non-interlaced, the signal 59 of Fig. 2 will occupy approximately one thirtieth of a second, and the retrace time 63 will or may occupy approximately one one hundred twentieth of a second. The constants of the switching circuit may be selected so that the signal 59a occupies one thirtieth of a second while the time delay between the signals 69a and 64a occupies one tenth of a second. This will result in a considerable slowing down of the image reproduced in the image signal reproducing device 118.

As has been stated in connection with the apparatus of Fig. 1 of the drawings, the series of image signals such as signals 59, 64, 66, etc., may be increased to any amount by increasing the number of image storage tubes 78. The image storage tubes may be very compact, particularly where spiral scanning is employed as pointed out above; and also, their operation does not depend on photoelectric action which also permits material reduction in size. A bank of such tubes may be arranged together in a relatively small space. The switching circuit 76 can be easily expanded with additional multivibrators to accommodate additional storage tubes 78.

The function of the switching circuit shown on Fig. 4 is as follows: It connects the grids of the storage tubes successively to the output of the video amplifier 24. In other words, it connects the grid of No. 1 storage tube 78 to the video input for the duration of the first frame, then the grid of the second tube for the second frame, etc. After one frame signal is applied to a tube, it is blanked by biasing the grid to cut off until its discharge cycle occurs. By using counter circuits, multivibrators, or the like in the switching circuit 76, a square wave step pulse is applied to the tubes in succession as shown on the curve 103 of Fig. 5. Since the storage tubes 78 and amplifier tubes 109, 112, and 114 are biased back to different negative values, electronic conduction will take place only when an adequately large positive signal is applied to their respective grids. The grids 83 of the storage tubes 78 are sufficiently positive during the charging and discharging period, controlled by multi-

vibrators or blocking oscillators running at a suitable frequency, determined by the time difference between the charge and discharge interval, while the grids 108, 110, and 111 of amplifier tubes 109, 112, and 114 are biased beyond cut off at all times except the discharge period.

Blocking oscillators in combination with counter circuits are fully described in the White patent above referred to.

A modified arrangement of the preferred embodiment of the invention disclosed in Fig. 4 is shown by Fig. 6. This modification discloses somewhat in detail an electronic switching and control circuit for controlling the operation of image storage tubes such, for example, as are indicated by reference character 78 in Fig. 4. With a view to simplifying the drawings, only two of these tubes 126 and 127 are shown. It will be understood, as stated previously in connection with Figs. 1 and 4 of the drawings, that the number of these tubes will be determined by the number of successive images of the rapidly occurring phenomena which are to be stored.

Composite signals from a transmitter such as the cathode ray scanning tube 10 of Fig. 1 of the drawings are applied to the grids of the storage tubes 126 and 127 through amplifiers 131 and 132. These composite signals are also applied through an integrating circuit 133 to a tube 134. The function of this integrating circuit is to remove the video and horizontal synchronizing and blanking signals from the vertical duration pulses. The signal on the plate 136 of the tube 134 will appear, accordingly, as indicated on the drawings, above the tube 134. These signals are designated 59' and 63'; whereas the incoming successive image signals are designated 59 and 63 and appear above the input connection 138.

The pulses 59' and 63' are fed to counter circuits 139 and 141 and will produce a potential increase in a series of steps designated 59'', 63'' as shown by the curve appearing above the tube 142. These potentials are then fed to blocking oscillator tubes 146 and 147 which are biased by sources of biasing potential shown conventionally as batteries 148 and 149 respectively. These batteries have potentials of opposite sign corresponding to the counter circuit output as shown in Fig. 5.

The blocking oscillators 146 and 147 are then triggered by the output of the counter circuit and since the pulse width is equal to the frame period, they apply a square wave on the grids of the storage tubes 126 and 127. In place of a blocking oscillator, any other type of relaxation oscillator may be used, such as multivibrators, dynatrons, pulsing gas discharge tubes, etc., provided their pulse width is approximately equal to the frame period, and the oscillating rate is comparatively slow.

The arrangement just described provides for the application of a positive potential to the proper grids of the proper storage tubes 126 and 127 at the time of transmission of successive frames.

A relaxation oscillator such as the multivibrator 151 has a repetition rate equal to the desired speed of the slow motion image. By way of example, this was indicated in connection with Fig. 3 as being 220 milliseconds and the pulses generated by this multivibrator are then applied to counter circuits 152 and 153 which trigger the multivibrators 156 and 157 successively in the manner in which the tubes 142 and 143 triggered

blocking oscillators 146 and 147, except at a delayed time rate.

The pulse width of the relaxation oscillators 156 and 157 is still equal to the frame period, but the repetition rate is considerably slower than that of the original frame frequency. These delayed pulses are fed to the grids of the storage tubes 126 and 127 and also to the grids of the amplifier tubes 159 and 161. It will be seen that each storage tube is biased back at all times, except for two pulses coinciding with the recording storage time and the discharge time. The amplifier tubes 159 and 161 are biased back at all times except during the discharge period.

In the slow motion systems of this invention, the higher the initial rate at which the successive images are stored, determined for example in Fig. 1 by the field frequency applied to the deflection means of the tube 10, the more the observing rate may be reduced.

It will be noted that while signals representing each frame or field of the image are discharged from the storage device at the original rate at which they were stored, initiation of the discharge of each field or frame is delayed or retarded as compared to its rate of storage.

Various modifications of the system shown and described herein by way of example are possible, without departing from the spirit and scope of the invention described herein, and it is desired that any and all of such modifications be considered within the purview of the present invention defined by the hereinafter appended claims.

Having now described the invention, what is claimed and desired to be secured by Letters Patent is the following:

1. In a system for reproducing images electrically in slow motion, means to store at a given rate signals representing said images to record successive steps of motion occurring in the images at the rate of occurrence of the motion, means to discharge signals representing said images at the rate of storage of said images, and means to delay the initiation of the discharge of each of said storage signals whereby the motion appears to occur at a rate differing from the rate of occurrence.

2. In a system for reproducing images electrically, means for generating a series of image signals in accordance with an optical image appearing in a field of view and at a predetermined rate, means for storing said image signals sequentially, and means for the increasingly delayed initiation of the discharge at the original storage rate of the said storage signals.

3. In a system for reproducing images electrically, means for generating, at a given rate, a series of image signals in accordance with an optical image appearing in a field of view, means for storing said image signals sequentially to record successive steps of motion occurring in the images at the rate of occurrence of the motion, means for discharging signals representative of said stored signals, said discharge occurring at the same rate as the storage of said signals and in the same sequence, and means for producing a time delay between each one of said series of discharge signals whereby the motion appears to occur at a rate differing from the rate of occurrence.

4. In a system for reproducing images electrically, means for generating a series of image signals in accordance with an optical image appearing in a field of view and at a predetermined rate, means for storing said image signals sequen-

5 tially, means for discharging signals representative of said stored signals said discharge occurring at the same rate as the storage of said signals, and means for the increasingly delayed initiation of the discharge at the original storage rate of the said storage signals.

5. In a system for reproducing images electrically, means for receiving a series of image signals representing a viewed image, a series of storage repeaters for storing said image signals sequentially, means for causing repetition of said stored signals sequentially at the rate of storage, and means for the increasingly delayed initiation of the discharge of said stored signals.

6. In a system for reproducing images electrically, means for receiving, at a given rate, a series of image signals representing a viewed image, a series of storage repeaters for storing said image signals sequentially, means for causing repetition of said stored signals, said repetition occurring at the same rate as the storage of said signals and in the same sequence, and means for producing a time delay between each one of said series of repeated signals.

7. A slow motion television transmitting system comprising a television pickup tube including a target electrode, means to generate a cathode ray beam, means to deflect said cathode ray beam in mutually perpendicular directions to scan said target electrode at a predetermined rate to produce image signals, a plurality of storage tubes each including a storage electrode, means to store the produced image signals on the storage electrodes of said tubes as electrostatic charges, means to remove said stored signals at a rate corresponding substantially to the rate of storage, and means for producing a time delay between the removal of a stored signal from one storage tube and the removal of a signal from the successive storage tube.

8. A slow motion television transmitting system comprising a television pickup tube including a light sensitive target electrode, means to produce an electrostatic charge image of a scene to be transmitted on said target electrode, means to generate a cathode ray beam, means to deflect said cathode ray beam in mutually perpendicular directions to scan said target electrode at a predetermined rate to produce image signals, a plurality of storage tubes each including a storage electrode, means sequentially to store the produced image signals on the storage electrodes of

said tubes as electrostatic charge image replicas of the image scanned in the said pickup tube, means sequentially to remove said stored image signals at substantially the same rate as the original production and storage rate, and means to produce a time delay between the removal of a stored signal from one storage tube and the removal of a signal from a successive storage tube.

9. A slow motion television transmitting system comprising a television pickup tube having a target electrode, means to generate a cathode ray beam in said tube, means to deflect said cathode ray beam in horizontal and vertical directions to scan said target electrode to produce image signals, a plurality of storage tubes each including a storage electrode, means including a switching arrangement successively to store the image signals produced during a number of vertical deflection signals on a separate storage tube, means including a second switching arrangement to remove said stored image signals in succession at a rate substantially equal to the rate at which they were originally produced, and means to produce a time delay between the removal of a stored signal from one storage tube and the removal of a stored signal from the successive storage tube.

10. A slow motion television transmitting system comprising a television pickup tube having a light sensitive target electrode, means to generate a cathode ray beam in said tube, means to deflect said cathode ray beam in horizontal and vertical directions at different rates to scan said target electrode to produce image signals corresponding to each television line and frame in accordance with the horizontal and vertical deflections of said cathode ray beam, a plurality of storage tubes each including an electron storage electrode, means including a switching arrangement operable sequentially to store the produced image signals representative of each television frame at the horizontal and vertical deflection rates on a separate storage tube, means including a second switching arrangement operable successively to remove said stored image signals at substantially the same rate as the rate at which they were originally produced and stored, and a switching arrangement controlling the initiation of each signal removal operation, the time of initiation being delayed from frame to frame of said storage cycle.

50 GEORGE C. SZIKLAI.
